UNITED STATES PATENT OFFICE.

MATHIAS T. SMITH, OF BOSTON, MASSACHUSETTS.

DESIGN FOR A CAMPAIGN-HELMET.

SPECIFICATION forming part of Design No. 25,850, dated August 4, 1896.

Application filed July 9, 1896. Serial No. 598,612. Term of patent 31 years.

To all whom it may concern:

Be it known that I, MATHIAS T. SMITH, of Boston, in the county of Suffolk and State of Massachusetts, have invented and produced 5 a new and original Design for Campaign-Helmets, of which the following is a specification, reference being had to the accompanying drawings, forming part thereof.

Figure 1 represents a front elevation of a 10 campaign-helmet illustrating my new design.

Fig. 2 represents a plan view thereof.

The particular feature of my new design for campaign-helmets consists in the design as herein shown and described.

15 In the drawings, 5 represents the front, and 6 the back of the helmet. These are similar in outline and general design, each having

the narrow ends 7 7 connected by the concave curved outlines 8 8 and the convex curve 9 and at the lower edge by the straight line 11. 20 From the front extends a plume 10, and on the front is the bead or border 12, following the curved outline, and the bead or border 13, following the straight outline. Between the front and the back are the cross-bars 14 25 and 15.

What I claim is—

The design for a campaign-helmet as herein shown and described.

MATHIAS T. SMITH.
